UNITED STATES PATENT OFFICE.

RICHARD SCHMIDT, OF MUNICH, GERMANY.

QUANTITY-METER.

No. 802,328.

Specification of Letters Patent.

Patented Oct. 17, 1905.

Application filed May 13, 1903. Serial No. 157,012.

To all whom it may concern:

Be it known that I, RICHARD SCHMIDT, a citizen of Germany, residing at Munich, Bavaria, Germany, have invented certain new and useful Improvements in Quantity-Meters; and I do hereby declare the following to be a full, clear, and exact description of the invention, such as will enable others skilled in the art to which it appertains to make and use the same.

Many attempts have been made hitherto to use spring-moved timepieces as quantity-meters—as, for instance, as current-meters. The constructions known for this purpose were based upon the principle to loaden the oscillating balance-spring more or less directly or indirectly by means of the current to be measured or by checking the oscillations of said balance-spring with the aid of an adjustable curve guide—as, for instance, by means of a curve checking at a suitable moment the movement of a pin secured to the spring and participating the oscillations of the same. Such apparatuses, however, were of a very complicated nature and involved always an undetachable connection between the clockwork and the mechanism influenced by the electric current. It was impossible hitherto to obtain in a simple easy manner a continuous proportional variation of the speed of the clockwork correspondingly to the proportional progressing movement of the apparatus influenced by the current.

The present invention is characterized by that the well-known regulator-lever of the balance-spring is put under influence of the quantity-meter in a manner that a proportional progressing of the meter involves always an adequate proportional movement of said regulator-lever modifying thereby conveniently the lead or lag of the clockwork. The present apparatus may be employed in all cases where the difference between a normal timepiece and a timepiece influenced in the above said manner is registered for measuring purposes.

In the accompanying drawings, Figure 1 is a front view of the clockwork. Fig. 2 is a back view of the balance and the mechanism connected therewith. Fig. 3 is a side elevation of the same. Fig. 4 shows, in greater scale, the balance-spring with the adjusting device. Fig. 5 is an elevation of the device connected to an ammeter.

In the drawings, *a* and *b* denote the clock-

hands for the minutes and hours. *c* is the hand for the seconds. The driving mechanism of the clockwork is exactly the like to that of the well-known spring-moved clockworks. For greater clearness sake the spring-case, driving mechanism, &c., have been omitted in the figures.

d denotes the balance, *e* the spiral spring mounted upon the same axle. *f* is the balance-vise to which the one end of the spring is fastened in known manner. (This fastening is shown only in Fig. 2 and has been omitted in Fig. 3.)

The present invention is based upon the well-known principle employed already for the regulating of spring-moved clockworks—viz., that the oscillation of a spring can be accelerated or retarded by respectively shortening or lengthening the spring.

The balance-vise *f* has a cylindrical sleeve *g*, through which the spindle of the balance passes and upon which sleeve the geared wheel *h* is mounted. By such an arrangement the weight of said gear-wheel is supported by the sleeve and not by the balance-spindle. On one side of said geared wheel *h* an arm *i* (regulator-lever) is fastened, (see Fig. 3,) holding, by means of a weak spring, a small block *k* in a manner that the latter is pressed against the free end of the spiral spring, separating thus the oscillating section of the spring from the unmoved section.

The block *k* has a play of a complete revolution. These parts are shown in an enlarged scale in Fig. 4. The block *k* softly presses the spiral spring against the one or the other of the two guide-posts *w* and *w'*, disposed in the known manner at both sides of the spiral spring. Such a disposition affords many peculiar advantages in the present meter where the regulating-block has a play of a complete revolution or more. The yieldingly-pressed regulating-block separates always sharply the swinging part of the spring from the motionless part and secures thus the desired proportionality in a manner that the scale *p* may be subdivided into equal parts.

As shown in the figures, the lever *i* when pushed to left shortens the swinging section of the spring and accelerates, therefore, the motion of the clockwork, so that the latter, which was driven normally—*i.e.*, as a normal timepiece—in the extreme right position of said block *k*, will now lead correspondingly.

In order to obtain a play as great as possi-

ble of the regulating-block—at least a complete revolution—and to enable also an exact adjusting (checking) of the same in any distinct position, the following arrangement has 5 been employed.

The pinion h meshes with the pinion n , mounted upon the axle m , holding (the latter) at its end over scale p a finger q . By shifting said finger q from one subdivision to the 10 other the regulating-block k will make always a corresponding way and shorten proportionally the swinging part of the spring.

The ciphers on scale p give the minutes or 15 seconds with which the timepiece leads, respectively, to a normal timepiece.

o denotes the normal position of the regulating-block. When shifting the same to left, the timepiece will lead with the seconds indicated. As already stated, the scale is 20 subdivided into equal parts, the acceleration and retardation of the spiral spring being directly proportional to the shortening or lengthening of the swinging spring-section.

As stated before, the play of the regulating-block shall be as great as possible, but at 25 least a complete revolution, so that on scale p we will have the considerable interval of, for instance, one hundred minutes in twenty-four hours—that is to say, the timepiece will 30 lead with one hundred minutes in twenty-four hours against a normal timepiece when finger q is upon subdivision “100.”

At both ends of scale p there are two checking-posts z and z' , limiting the stroke of the 35 finger q . Sometimes it may be desirable to stop the timepiece when the finger q is shifted to the checking-post z' . In such cases the following arrangement may be employed: The wire r , mounted yieldingly at u , will be 40 held by means of a small spring s in its normal position, in which it rests on nave t of pinion n . At a certain determined position of pinion n a pin ch integral with said pinion releases said wire r , so that the latter will 45 swing out and push the yielding wire v against the balance, stopping thus the motion of the timepiece.

The present time-meter can be used in all 50 cases where quantities—as, for instance, quantities of power, (force,) energy, &c.—are measured by means of time differences. When using it, for instance, as current-meter, (like the Aaron meter,) the present timepiece will have the function of the pendulum influenced 55 by the electric current. For this purpose it needs only to connect lever q with an apparatus influenced by the electric current, (as ampere-meter or the like,) such as indicated at A , whose index A' is connected to the lever 60 q , through suitable connections $A^2 A^3 A^4$, as shown in Fig. 5, in such a manner that said lever (or finger) will be adjusted always correspondingly to the current intensity. Over pendulum-meters such a current-meter would 65 have the great advantage of a very compendi-

ous and cheap construction. It could be also advantageously employed on moving parts, as tram-cars or the like, for controlling and measuring the current consumption. A normal timepiece designed for the comparison 70 may be provided for, having, for instance, the same dial and the same balance-spring.

Over the meters with balance-springs based upon the principles as stated in the preamble of this specification the present timepiece has 75 the advantage that it leads always proportionally and correspondingly to the motion of the meter. Its construction is thereby as simple as possible. It has, further, no parts of a considerable mass which could be influenced in their movement by vibrations or jolts. The same timepiece may be also used for different meters, as it is only necessary to mount the latter simply upon the spindle, (if necessary, with a suitable reduction mechanism). This was impossible with the meters known hitherto. 85

What I claim as my invention is—

1. In a quantity-meter, the combination, with a balance-vise provided with a sleeve, 90 a balance-spindle having one end journaled in the balance-vise and passing freely through said sleeve, and a balance-wheel upon the balance-spindle, of a balance-spring connected to the spindle and to the 95 balance-vise, a regulating-wheel mounted rotatably upon the sleeve of the balance-vise, a regulator device attached to said wheel and arranged to control the operation of the balance-spring, and electrically-operated 100 means for moving said regulating-wheel.

2. In a quantity-meter, the combination, with a balance-vise, a balance-spindle having one end journaled in the balance-vise, a balance-wheel and a balance-spring upon 105 the balance-spindle, and a regulator-lever arranged to control the balance-spring, a regulating-pinion arranged to actuate said regulator-lever, a gear-wheel in mesh with said pinion, and electrically-operated means 110 for operating said gear-wheel.

3. In a quantity-meter, the combination, with a balance-spindle, a balance-wheel and a balance-spring connected to said spindle, and a regulator-lever for controlling said 115 spring, of a regulator-block yieldingly mounted on said regulator-lever and arranged to bear against said balance-spring and electrically-operated means for operating said regulator-lever. 120

4. In a quantity-meter, the combination, with a balance-spindle, a balance-wheel and a balance-spring connected to said spindle, and a regulator device arranged to control the balance-spring, of a pinion to which 125 said lever is connected, a gear-wheel arranged to engage said pinion, a pointer-lever attached to said gear-wheel, a dial over which said pointer-lever moves, and electrically-operated means for moving said pointer-lever. 130

5. In a quantity-meter, the combination, with a balance-spindle, a balance-wheel and a balance-spring connected to said spindle, and a regulator-lever arranged to control the balance-spring, of a pinion to which said lever is connected, a gear-wheel in mesh with the pinion, a pin in said gear-wheel, a stopping device operated by said pin and arranged to stop the balance-wheel, and elec-

trically-operated means for moving said 10 gear-wheels.

In testimony whereof I affix my signature in presence of two witnesses.

RICHARD SCHMIDT.
